UNITED STATES PATENT OFFICE.

JOHN J. BUCHANAN, OF WATERBURY, CONNECTICUT, ASSIGNOR TO WATERBURY BUCKLE CO., OF WATERBURY, CONNECTICUT, A CORPORATION.

SUSPENDER-BUCKLE.

No. 895,068.

Specification of Letters Patent.

Patented Aug. 4, 1908.

Application filed April 6, 1908. Serial No. 425,462.

To all whom it may concern:

Be it known that I, JOHN J. BUCHANAN, a citizen of the United States, residing at Waterbury, in the county of New Haven and State of Connecticut, have invented a new and useful Improvement in Suspender-Buckles; and I do hereby declare the following, when taken in connection with the accompanying drawings and the letters of reference marked thereon, to be a full, clear, and exact description of the same, and which said drawings constitute part of this specification, and represent, in—

Figure 1 a view in front elevation of a suspender-buckle constructed in accordance with my invention. Fig. 2 a detached view thereof on a larger scale, the clamping-lever of the buckle being shown in its full open position. Fig. 3 an edge view of the buckle shown as webbed and with the lever partially open. Fig. 4 a detached view of the pivotal finger-piece. Fig. 5 a broken view of a buckle illustrative of the prior art, this buckle having its clamping-lever provided with a finger-piece having no stop-finger, whereby the finger-piece is liable to be swung inward so as to foul the lever and prevent it from being closed as shown in this figure.

My invention relates to an improvement in suspender buckles of that class in which the clamping-lever is furnished with a depending pivotal finger-piece, the object being to provide means for preventing the finger-piece from swinging inward so as to foul the lever and prevent it from being crowded down into its closed position.

With these ends in view my invention consists in a suspender buckle having certain details of construction as will be hereinafter described and pointed out in the claims.

In carrying out my invention as herein shown, I provide the pivotal finger-piece 2 with a stop-finger 3 located in its plane and extending upward at a right angle from its suspension-bar 4 midway the length thereof, the said bar being located in a horizontal sleeve 5 formed upon the lower end of the outer arm or body 6 of the sheet-metal clamping-lever of the buckle. As shown the stop-finger 3 is formed by extending at one end of the wire from which the finger piece 2 is

formed, but I do not limit myself to producing the said stop-finger in any particular way. For the clearance of the said stop-finger 3, the sleeve 5 is formed with a centrally arranged notch 6^a permitting the finger 3 to swing with the finger-piece 2 and to engage with the inner face of the outer arm or body 6 of the clamping-lever the short arm or clamping edge 7 of which engages with the webbing 8 and presses the same against the yielding-back plate 9 of the buckle-frame which also comprises a wire loop 10 upon which the lever is pivotally mounted in the usual manner, the lever being provided for this purpose, as shown, with sleeves 11 receiving the trunnions 12 formed by the ends of the wire loop 10. But the specific construction of the buckle may be varied as desired, my present invention relating only to the provision of the finger-piece 2 with a stop-finger 3. This stop-finger does not prevent the finger-piece 2 from being swung outward upon its suspension bar 4 as shown by broken lines in Fig. 3 for the more convenient grasping and operation of the clamping-lever of the buckle, but it does prevent the finger-piece from being swung inward so as to foul the lever and prevent the same from being crowded down into its closed position as shown by Fig. 5 which illustrates a buckle having a pivotal piece as now constructed without the stop furnished by my invention.

I claim:

In a suspender buckle, the combination with a buckle-frame, of a clamping-lever pivotally connected with the said frame, and a pivotal finger-piece depending from the outer arm of the said clamping-lever and provided with a stop constructed and arranged to engage the inner face of the said arm of the clamping lever, whereby the said finger-piece is prevented from swinging inward under the said lever and so prevent the same from being crowded into its closed position.

In testimony whereof, I have signed this specification in the presence of two subscribing witnesses.

JOHN J. BUCHANAN.
